UNITED STATES PATENT OFFICE.

JOSEPH WELKER, JR., OF CENTRAL FALLS, ASSIGNOR TO JOHN M. PARKER,
OF PAWTUCKET, RHODE ISLAND.

MACHINE FOR FEEDING BLANKS TO LATHES.

SPECIFICATION forming part of Letters Patent No. 317,601, dated May 12, 1885.

Application filed June 25, 1884. (No model.)

To all whom it may concern:

Be it known that I, JOSEPH WELKER, Jr., of Central Falls, in the county of Providence and State of Rhode Island, have invented a new and useful Improvement in Machines for Feeding Blanks to Gage-Lathes; and I do hereby declare the following specification, taken in connection with the accompanying drawings, forming a part of the same, to be a description thereof.

This invention relates to a machine for feeding spool or other blanks to a gage-lathe to be turned; and it consists in certain features of construction, as hereinafter described and set forth in the claims.

Referring to the drawings, Figure 1 represents a top view of a machine embodying the invention, and a gage-lathe with which the said machine can be combined. Fig. 2 shows a side view and partial section of the machine and the lathe. Fig. 3 represents an end view of the machine with the hopper for holding the blanks in section. Figs. 4, 5, and 6, show several parts of the machine in certain positions. Fig. 7 represents an end view of the lower part of the conveyer or chute.

The machine is provided with a hopper, A, for holding a mass of blanks which have preferably been bored with substantially central holes and have been "roughed" into the shape of cylinders.

For convenience in introducing the blanks into the hopper, and in order that a large supply of blanks may be furnished, the hopper is preferably provided with an inclined extension, A'. The sides of the hopper are preferably made to converge laterally at the bottom, as shown in Fig. 2, in order that the blanks shall seek the lowest plane, and the hopper is preferably provided with a central groove, a, of a width slightly greater than the diameter of a blank, in order that the blanks may lie lengthwise therein.

For removing the blanks from the hopper, a roulette, B, is employed, which is composed of arms, b, each having near its outer end a spur, b', of a diameter adapted to enter the bore of a blank, although in place of these spurs, scoops or spring-fingers may be secured to the arms b to take up the blanks. The roulette B is mounted on a shaft, B', which has

a bevel-gear, b², on one end, and this gear meshes with a gear, b³, on the shaft B'. This shaft is provided with a pulley, b⁴, which is driven by a belt from any convenient source of power, as a counter-shaft, or from a pulley, c, on the main shaft of the lathe C, as shown in Fig. 1. The roulette is revolved in the direction of the arrow, Figs. 3 and 4, and as the outer ends of its arms pass through the groove a the spurs b' enter the holes in the blanks lying therein and take up the blanks D, as shown in Fig. 4.

For receiving the blanks from the roulette and carrying them toward the lathe, an inclined conveyer or chute, E, is furnished, which is pivoted or otherwise secured to a standard on the frame of the machine, as shown in Figs. 2, 3, and 6. Attached to the upper end of the conveyer E are two ways, e and e', Fig. 1, which are separated by a space sufficient to allow the arms of the roulette B to pass between them.

For removing the blanks from the arms of the roulette, a pawl or stripper, F, is employed, which is pivoted to an arm, F'. This arm is pivoted to a stud, f, and has a projection or roller, f', which enters a slot in a cam, F², mounted on the shaft B², the said cam acting to reciprocate the pawl or stripper F.

For guiding the pawl in its movements, one of the ways, as e, is preferably furnished with an upwardly-projecting flange, e², upon which rides a roller, f², secured to the side of the pawl at its outer end. This end of the pawl is preferably supplied with a pivoted finger, f³, which, as the pawl is moved outwardly, rides over the blank on an arm of the roulette, and falls behind the blank, as shown in Fig. 4. By the action of the cam F² the pawl F is advanced or moved inwardly to strip a blank from an arm, b, of the roulette and pull the blank along the ways e e' to a position in front of the upper end of the conveyer E, as shown in Figs. 2 and 3. In order to guard a blank being carried by its momentum (when the machine is run at high speed) beyond the proper position on the ways where it should be left by the pawl F, springs f⁴, Figs. 1 and 5, or other suitable means, are preferably employed to create friction upon the blank as it is moved along the ways.

The blank is removed from the ways into the conveyer E by a second pawl, G, Figs. 2 and 5, which is pivoted to an arm, G'. This arm is pivoted to a stud, g, Fig. 5, and bears 5 a projection or roller, g', which is held in engagement with a cam, G², Figs. 1 and 5, on the shaft B² by a spring, g³, Figs. 1 and 5. When the blank is left by the pawl F in the position described, the pawl G has been moved 10 to the position shown in Fig. 2. The cam G² now acts to advance the pawl G and cause it to remove the blank from the ways into the conveyer, as shown in Fig. 5, down which the blank rolls, and falls on ledges e³ e³ projecting 15 inwardly from the conveyer sides, as shown in Figs. 2 and 7. The movements of the pawls F and G are so timed with relation to the movement of the roulette B that as each arm b of the latter brings up a blank the said 20 pawls remove the blanks from the arms to the conveyer.

As some of the arms b may occasionally fail to pick up a blank provision is made for keeping the conveyer supplied with blanks 25 by revolving the roulette at a greater speed than would be necessary should each arm always take up a blank; and as each of the arms b may take up blanks for some time continuously, it is necessary that provision be made 30 for the escape from the ways e e' of such blanks as cannot enter the conveyer should it be full. If the conveyer be full at a time when a fresh blank is moved toward it by the pawl G, the uppermost blank in the conveyer 35 will prevent the entrance of such fresh blank, which will roll back into the ways e e' when the pawl retreats.

As shown in Figs. 1 and 3, the rear ends of the ways are connected by a bridge, e⁴, and 40 this bridge is arched sufficiently to allow a blank to pass under it, so that as a second fresh blank is brought along the ways by the pawl F, the rejected blank lying in the ways can be pushed by the advancing blank under 45 the bridge and out of the ways, when it will fall into the hopper A. If preferred, however, the rear ends of the ways beyond the conveyer may be sufficiently separated laterally to allow a rejected blank to drop through 50 between them when it is pushed along as described.

Since an attempt to introduce a fresh blank into the conveyer at a time when it is full would tend to force up out of line one or more 55 blanks lying in the conveyer, the sides of the latter are preferably provided with attached inner bars or suitable flanges, e⁵ e⁵, which overlie the ends of the blanks and prevent them from being forced upward, although a single 60 bar may be employed to overlie the blanks for such purpose, if desired.

From the ledges e³ the blank is removed to be turned to the lathe-centers e' e², and for this purpose any suitable carrier may be employed. The carrier shown in the drawings 65 consists of two fingers, H H'. The finger H has a notch in its front end for engaging the

blank, and is arranged to slide on the standard H². The finger H' is pivoted to an arm, h', which is adjustably secured to a stud, h², 70 projecting downwardly from the finger H, as shown in Figs. 2 and 6, and a spring, h³, is employed for causing the finger H' to hold the blank against the notched end of the finger H during the movement of the blank by said fingers. When the blank falls upon the ledges e³ the fingers H H' are in a rearward position, 75 as shown in Fig. 2, and to allow the blank to enter between them a stop-rod, h⁴, secured to the standard H², is used to hold the upper end 80 of the finger H' slightly advanced. To the finger H a link, h, is pivoted, which link is connected to the long arm of a bell-crank lever, I, the short arm of which bears a projection or a roller which enters a slot in the side of a cam, I', on the shaft B², Fig. 6, the said cam 85 acting to reciprocate said finger. The cam I', however, may be located on a shaft on the lathe C, if desired, and a suitable bell-crank lever and link be employed to cause the 90 cam to reciprocate the fingers H H', as will be readily understood. As the fingers H H' move forward under the action of the cam I', the finger H' leaves the stop-rod h⁴ and is closed by the spring h³ against the front of the blank, 95 thereby firmly holding the same in the notched end of the finger H. During the advance of the fingers the lowermost blank in the conveyer E is prevented from falling by the finger H, which acts as a cut-off and supports 100 such blank, as shown in Fig. 6. The cam I' advances the fingers H H' until the bore of the blank held by said fingers is in alignment with the lathe-centers e' e², when the former center is moved forward by suitable means to 105 enter the bore of the blank and force the blank upon the live-center e², which revolves the blank, in order that a tool, C, on the lathe C may turn the blank to the desired shape. The center e' having moved forward to take the 110 blank, the fingers are retracted to the position shown in Fig. 2, to take a fresh blank. As the fingers move rearward, the finger H' is turned 115 on its pivot by the blank, so as to clear the latter, the spring h³ at its point of attachment to said finger passing below said pivot and holding the finger open. During the retreat of the fingers to their rearward position the curved end of the finger H' engages a stop-rod, 120 h⁵, which turns the finger back to its normal position. If desired, however, the rod h⁵ may be dispensed with and the finger H' be pivoted to the arm h' at a point sufficiently below 125 the point where the spring h³ is attached to said finger to cause said spring to return the finger to its normal position when it clears the blank, as will be readily understood.

In order to prevent a blank from being crushed or injured, and the finger mechanism from being damaged, should a blank be accidentally caught on the upper point of the notched end of the finger H, the conveyer E is preferably provided with pivoted spring-latches e⁶ e⁶, which will swing outward under 130

sufficient pressure, and thereby allow the blank so caught to escape.

In order to adapt the machine to feed to a gage-lathe blanks of various sizes within certain limits, the sides of the hopper A are preferably made adjustable laterally, and are held in a proper relation to each other by suitable means, such as bolts and nuts J, j, Figs. 1 and 3.

For conveniently adjusting the hopper sides their feet A² are preferably mounted to slide on rods or bearings K, and a right and left hand screw, L, is employed to move said sides laterally with relation to each other, the said screw being furnished with collars l, which bear against a stud, m, on the base M, Figs. 2 and 3. By loosening the nuts j and turning the screw L in the proper direction the hopper-sides can be made to approach or to recede from each other, thereby narrowing or widening the groove a, according to the diameter of the blanks to be fed. As shown in Fig. 2, the bottom of the groove a is made substantially V shape, so that when the groove is widened to admit blanks of larger diameter, or narrowed for blanks of smaller diameter, such blanks, respectively, will occupy a lower or a higher plane on the doubly-inclined bottom of the groove, thereby bringing the bores of the blanks into proper position to receive the spurs b' on the arms of the roulette. If desired, however, instead of making the hopper sides adjustable laterally, or in addition thereto, the arms b of the roulette may be adjustable lengthwise, so as to bring the spurs b' into proper positions to take up the blanks, as will be readily understood. The bars e⁵ on the conveyer E are also preferably made adjustable vertically, to accommodate blanks of different diameters, the said bars being secured to the conveyer sides by thumb-screws n, Fig. 1, or other suitable means.

In order to allow the conveyer E to receive blanks of different lengths one of its sides, e', is preferably made laterally adjustable with relation to the other side. For this purpose the side e' is provided with slotted lugs e⁸, Fig. 1, which are secured by thumb-screws or other suitable means, n', to lugs e⁹, Fig. 3, projecting from the conveyer-bottom. The ledges e⁸ e' on the conveyer are also preferably made vertically adjustable to receive blanks of different diameters, so that the axes of the blanks shall be in a proper relation to the notched end of the finger H, the said ledges being secured to the sides of the conveyer by thumb-screws n², Fig. 7.

Although I prefer to employ the pawl G to remove the blanks from the ways e e' to the conveyer E, yet, if desired, the said pawl may be dispensed with, and the upper end of the conveyer be located in such relation to the ways that when the blanks are moved by the stripper F to a position in front of the conveyer they will roll into the latter by their own gravity, as will be readily understood.

Preferably the conveyer E is pivoted to its supporting-standard or is otherwise mounted,

so that its upper end, or both of its ends, are vertically adjustable, so that it can be brought into proper relation to the roulette to receive therefrom blanks of any size.

What I claim, and desire to secure by Letters Patent, is—

1. The combination, with a hopper for holding a mass of blanks, having converging sides and formed with a central groove in its bottom, of a roulette supported above said bottom to revolve in said hopper and groove and provided with lateral spurs to enter and engage with said blanks to remove the same from the hopper, substantially as described.

2. The combination of a hopper for holding a mass of blanks, formed with a grooved bottom for positioning said blanks, and a roulette supported above said bottom to revolve in said hopper and groove and provided with lateral spurs to engage with said blanks to remove the same from the hopper, the bottom of said hopper and the roulette being relatively adjustable, substantially as described, to enable blanks of different sizes to be engaged by the spurs on the roulette for the removal of the blanks from the hopper, substantially as described.

3. The combination, substantially as hereinbefore set forth, of a hopper having a groove with an inclined bottom and adjustable sides and a roulette arranged to revolve in said hopper and groove, and provided with suitable means, as described, for removing the blanks therefrom.

4. The combination of a hopper for holding a mass of blanks, a roulette supported to revolve in said hopper and provided with spurs to engage with said blanks to lift them from the hopper, a conveyer arranged adjacent to the discharging-point of said roulette, and a stripper for removing said blanks from the spurs of the roulette for their passage to said conveyer, substantially as described.

5. The combination of a hopper for holding a mass of blanks, a roulette supported to revolve in said hopper and provided with spurs to engage with said blanks to lift them from the hopper, a stripper adjacent to the discharging-point of the roulette to remove the blanks from its spurs, ways located to receive the blanks as removed from the roulette, a conveyer to receive the blank from off said ways, and a movable propeller for removing the blanks from the ways into the conveyer, substantially as described.

6. The combination of a hopper for holding a mass of blanks, a roulette supported to revolve in said hopper and provided with spurs to engage with said blanks to lift them from the hopper, a stripper adjacent to the discharging-point of the roulette to remove the blanks from its spurs, ways to support said blanks in their passage from the roulette, said ways being open at or near their rear ends to allow the discharge of a rejected blank, and a conveyer connecting with said ways at a point between their open ends and the point

- where the ways receive the blanks from the roulette, substantially as described.
7. The combination of a hopper for holding a mass of blanks, a roulette supported to revolve in said hopper and provided with spurs to engage with said blanks to lift them from the hopper, a stripper adjacent to the discharging-point of the roulette to remove the blanks from its spurs, ways for receiving said blanks as removed from the roulette, and yielding bearings secured to said ways to produce a friction upon the blanks as they move along the ways, substantially as described.
8. The combination of a hopper for holding a mass of blanks, a roulette supported to revolve in said hopper and provided with spurs to engage with said blanks to lift them from the hopper, a stripper adjacent to the discharging-point of the roulette to remove the blanks from its spurs, a conveyer to receive said blanks subsequent to their removal from the roulette, and a slide at the lower end of the conveyer to permit one blank at a time to pass from the conveyer, substantially as described.
9. The combination of a hopper for holding a mass of blanks, a roulette supported to revolve in the hopper and provided with spurs to engage with the blanks to lift them from the hopper, a stripper adjacent to the discharging-point of the roulette to remove the blanks from its spurs, and a conveyer vertically adjustable with relation to the roulette to receive the blanks removed from said roulette, substantially as described.
10. The combination, with a hopper for holding a mass of blanks, of a roulette supported to revolve in said hopper and provided with spurs to enter and lift the blanks therefrom, and a conveyer to receive said blanks subsequent to their removal from the roulette, said conveyer having an adjustable side to accommodate blanks of different lengths, substantially as described.
11. In a machine for feeding blanks to a gage-lathe, the combination, with the lathe and a hopper and roulette for removing blanks from the hopper, of a conveyer, E, located between the lathe and hopper, and a bar or bars, e^5 , vertically adjustable on the conveyer to retain blanks of different diameters, substantially as described.
12. In a machine for feeding blanks to a gage-lathe, the combination, with the lathe and a hopper and roulette for removing blanks from the hopper, of a conveyer, E, located between the lathe and hopper, and adjustable ledges e^3 , located beneath the conveyer at the end next to the lathe, substantially as described.
13. In a machine for feeding blanks to a gage-lathe, the combination, with the lathe and a hopper and roulette for removing blanks from the hopper, of the conveyer E, located between the hopper and lathe, a sliding finger, H, beneath the conveyer at the end next to the lathe, and spring-latches e^6 at the same end of the conveyer, substantially as described.
14. In a machine for feeding blanks to a gage-lathe, the combination, with a lathe and a hopper and roulette for removing blanks from the hopper, of the conveyer E, located between the hopper and lathe, adjustable ledges e^3 , located beneath the conveyer at the end next to the lathe, pivoted finger H' , extending above the ledge e^3 , and sliding finger H, moving across said ledge, substantially as described.
15. In a machine for feeding blanks to a gage-lathe, the combination, with a lathe and conveyer for supplying blanks thereto, of the sliding finger H, located at the lower end of the conveyer, the finger H' , located in front of finger H and hinged to an arm, h' , adjustably connected with finger H, and spring h^3 , connecting finger H' with arm h' , substantially as described.
16. In a machine for feeding blanks to a gage-lathe, the combination, with a lathe and conveyer for supplying blanks thereto, of the sliding finger H, located at the lower end of said conveyer, the finger H' , in front of finger H and hinged to an arm, h' , connected with said last finger H, and stop-rods $h^4 h^5$, one located above and the other below the hinged point of finger H' , substantially as described.
17. In a machine for feeding blanks to a gage-lathe, the combination, with a lathe and conveyer leading thereto, of a hopper formed in two parts adjustable to and from each other and having a central groove in its lower portion whose groove is V-shaped, and a roulette having arms radiating from a hub provided with spurs at their outer ends and supported to revolve in the hoppers, substantially as described.
18. In a machine for feeding blanks to a gage-lathe, the combination, with the lathe and hopper, of a conveyer from which one blank at a time is fed to the lathe as received from the hopper, a roller revolving in the hopper and having spurs which lift blanks therefrom, ways $e^3 e'$ for receiving blanks as delivered from the roulette, a reciprocating stripper, F, for removing blanks from the spurs of the roulette to the ways $e^3 e'$, and a reciprocating pawl, G, for removing the blanks from said ways to the conveyer, substantially as described.
19. In a machine for feeding blanks to a gage-lathe, the combination of a lathe, a conveyer from which one blank at a time is fed to the lathe, a hopper for holding a mass of blanks, a roulette revolving in the hopper and having spurs for lifting blanks therefrom, a reciprocating stripper for removing the blanks from the spurs of the roulette, ways for receiving the blanks from the roulette, and a reciprocating pawl for removing the blanks from said ways to the conveyer, substantially as described.
